UNITED STATES PATENT OFFICE.

WILLIAM SMITH, ROBERT LAIDLAW SMITH, AND CECIL SANDYS WALKER, OF
WESTMINSTER, LONDON, ENGLAND.

TILE OR SLAB.

950,060.

Specification of Letters Patent. Patented Feb. 22, 1910.

Application filed February 8, 1908. Serial No. 414,118.

To all whom it may concern:

Be it known that we, WILLIAM SMITH, ROBERT LAIDLAW SMITH, and CECIL SANDYS WALKER, all subjects of the King of Great Britain, residing at 11 Tothill street, Westminster, in the county of London, England, have invented certain new and useful Improvements in Tiles or Slabs, of which the following is a specification.

10 This invention relates to tiles or slabs for use in building fire resisting floors, walls, partitions and the like, composed of concrete or similar plastic materials reinforced with metal. When such tiles or slabs have been used for reinforced floor constructions it has hitherto been proposed to make them flat and to suspend them by means of embedded and projecting metal clips from bars or supports extending between the usual 15 girders etc. so as to form a permanent centering on which the concrete or other filling is laid. In such cases the adhesion between the flat tile and the filling is imperfect and the flooring is mainly suspended by the 20 metal clips which may rust. In some cases, as permanent centering between joists, tiles or slabs have been used having longitudinal inclined projections and lateral ribs and suspended by resting them on the flanges of the 25 joists.

The object of the present invention is to produce tiles or slabs for reinforced floor, wall, and the like constructions which slabs have lateral ribs and inclined projections 30 and are secured to the supporting bars by means of wires embedded in and projecting from the tiles or slabs, so as to temporarily secure the tiles in position during the time 35 the concrete filling is setting, after which 40 the tile and the filling are keyed together and become homogeneous with the supporting bars.

In the accompanying drawings Figure I is a section taken on the line 1—1 of Fig. 45 II, and Fig. II is a plan of one of our improved fire-resisting tiles or slabs as used for floors; and Fig. III is a vertical section of part of a floor showing the mode of using the improved tiles or slabs shown in Figs I 50 and II, the reinforcement *k* seen in Fig. I being here omitted.

The same letters of reference where they occur are used to denote the same or corre-

sponding parts in all the figures of the drawings.

Our improved tile or slab is made of concrete or other plastic fire-resisting material cast in a mold at a factory and then sent out as required to the place where the constructional work is to be done.

In the form shown, the tile or slab is cast with inclined projections *a* which extend longitudinally from end to end as shown in Fig. II and with transverse ribs *b* which project laterally from the inclined projections *a* and on both sides thereof at suitable distances apart. Where the tile or slab is provided with more than one inclined projection *a*, as in the example shown in Figs. I and II where two such inclined projections are shown formed on the tile or slab, the lateral ribs *b* of the two inclined projections are cast in line, and a space *c* is left between the contiguous ribs just sufficiently wide to admit the metal bars *d* forming the stiffening members of the floor, on which bars the tiles or slabs are to be suspended.

Cast in with the concrete when the tile or slab is molded is a length of wire *e* having projecting ends *e'*. These wires *e* pass through the inclined projections and ribs of the tile or slab, as shown in Figs. I and II, and the ends *e'* of the wires of contiguous inclined projections and ribs are twisted together over the top of the metal 80 suspending bars *d* of the floor as shown in Fig. III, thereby temporarily securing the tiles or slabs in position. Instead of casting the wire in with the tile short lengths may be used threaded through holes made in the 85 tile with the ends of said wires projecting through the ribs; and the wires may be secured otherwise than by casting in the tile or slab.

The mode of building a floor with our 90 improved tiles or slabs will now be understood. The bars *d* are first placed in position on the bearings at the ends of the span, and a tile or slab is passed up from underneath with the space *c* into which fits the 100 bar *d*, whereupon the ends *e'* of two contiguous wires *e* are twisted together over the top of the bar *d*, as shown at *e*² in Fig. III, and the tile or slab thus temporarily secured to the bar *d*; the bar *d* being also held firmly 105 in position by the wires *e'* and by the ribs *b*.

The next tile is passed up and similarly secured until the ceiling construction is completed, whereupon concrete *f* or other plastic material is rammed in to the desired height 5 to make the floor. The projections are inclined and so disposed that when *in situ*, as shown in Fig. III, they inclose between them a space such as *g* thereby providing an undercut recess into which the filling *f* will 10 enter and take a substantial hold such as to make the filling and tile or slab a practically homogeneous structure.

As shown in Fig. I each tile or slab is provided with a projection *h* extending 15 longitudinally along one edge and with a corresponding rabbet *j* along the other edge so that when placed in position the projection *h* of one tile engages in the rabbet *j* in the next forming a rabbeted joint. The 20 tile or slab shown is provided, at about the middle thickness of the base, with an inset *k* of wire gauze, wires interlaced or crossed, expanded metal, or other suitable metal fabric adapted to form a key for the plastic 25 material and serving to reinforce the tile or slab at the base; but this metal reinforcement is not part of our invention and may be dispensed with.

Having fully described our invention,

what we claim and desire to secure by 30 Letters Patent is:—

1. A fire-resisting tile or slab for floor constructions provided on one face with longitudinal inclined projections, and ribs extending transversely of the tile and intersecting the longitudinal projections, and securing wires embedded in the tile underneath the ribs and longitudinally of the same and having their ends projecting at the rear of the tile. 40

2. A fire-resisting tile or slab for floor constructions provided on one face with longitudinal inclined projections, and ribs extending transversely of the tile and intersecting the longitudinal projections, and securing wires threaded through holes made in the tiles underneath the ribs and longitudinally of the same, the ends of the wires projecting at the rear of the tile. 45

In testimony whereof we have hereunto 50 set our hands in presence of two subscribing witnesses this 24th day of January 1908.

WILLIAM SMITH.

ROBERT LAIDLAW SMITH.

CECIL SANDYS WALKER.
